J. H. ACKROYD,

GAS BURNER,

APPLICATION FILED FEB. 20, 1919.

1,343,700.

Patented June 15, 1920.

INVENTOR.

JOHN H. ACKROYD.

14 BY George E. Hale

ATTY.

UNITED STATES PATENT OFFICE.

JOHN H. ACKROYD, OF MILFORD, CONNECTICUT.

GAS-BURNER.

1,343,700.

Specification of Letters Patent. Patented June 15, 1920.

Application filed February 20, 1919. Serial No. 273,244.

To all whom it may concern:

Be it known that I, JOHN H. ACKROYD, a citizen of the United States, residing at Milford, in the county of New Haven and State 5 of Connecticut, have invented certain new and useful Improvements in Gas-Burners, of which the following is a specification, reference being had therein to the accompanying drawings.

10 The present invention has relation to burners of a type which consume a gaseous fuel and has as one of its objects, among other things, to construct an efficient burner. Accordingly, the burner is provided with a 15 multiplicity of burner tubes or burner units, arranged in positions relatively to each other and to baffle posts or baffle units surrounding the burner tubes, so that an equal supply of air is supplied to each and every flame jet 20 through air passages defined by said baffles and burner tubes and located in the same plane as the burner and baffle posts but in a plane below a combustion space or chamber inclosed by a flange or guard surrounding 25 the flame jets.

Another object of the invention is to construct the burner of as few separable sections as possible so as to facilitate manufacture and assemblage of the burner.

30 The invention will be hereinafter described and ascertained, and an embodiment thereof is illustrated in the accompanying drawings, wherein:

Figure 1 is a side elevation of the burner shown with a gas supply pipe connected thereto;

Fig. 2 is a plan view of the burner; and

Fig. 3 is a sectional view taken upon line 3—3 of Fig. 2 looking in the direction of the 40 arrow, and in this figure the burner is represented as being seated in an opening at the bottom of an oven of which only a fragmentary part is shown.

The improved burner, as illustrated, is 45 constructed of three parts, namely, the body portion 1, the lower portion or gas distributor 2 and the upper portion or covering member 3. The component parts of the body portion 1 are preferably all integral there- 50 with and consist of the base 4 having an opening 5 with its flanged side walls internally threaded at 6. A plurality of burner tubes or posts 7 extend upwardly from the base 4 and are arranged by rows in a par- 55 ticular manner and for a purpose, as will be hereinafter set forth. A series of baffle

posts 8, equally spaced apart, surround the burner tubes or posts 7. These latter posts 7 have each a central bore 9, preferably reduced at the upper end, and provide a re- 60 stricted gas passage. Also to increase the area of the air passages toward the top, for reasons hereinafter stated, the burner tubes 7 and baffle posts 8 diminish preferably in diameter from the base upward. The gas 65 distributer 2, consists of the plate or base 10, preferably circular in shape and having the edge thereof threaded at 11 to engage the threads 6 of the body portion. When this member 2 is screwed or otherwise secured 70 in place, the chambered portion 12 of the member 2 forms an inclosed gas distributing chamber, to which chamber, gas is supplied through pipe 13 fitting in the threaded opening 14 of the member 2. A space 15 is left 75 between the top of the member 2 and the base 4 of the body member 1 so that the gas will be equally distributed through the pas- 80 sages 9 in the tubes 7.

The upper or covering member 3 includes 85 as component integral parts a plate or base 16 having a ledge 17 around the outer edge so as to seat the burner in an opening 18 when the burner is to be inclosed within an oven 19 for example. A vertical flange or 90 flame guard 20 projects upwardly from the base 16 and the shape of the flange or flame guard is in conformity with the grouping of the burner tubes 7. This flange 20 incloses the space immediately above the burner tubes 95 on all sides and thus forms a combustion chamber for the flame jets. At various points, the flange 20 is offset at 21 to permit locating of screws 22, whereby the member 3 is secured to the body portion 1 by engage- 100 ment of said screws in threaded holes (not shown) in the posts 8. The bottom of the plate 16 is in the same plane as the top sur- 105 face of the burner tubes 7 and rests on the baffle posts 8. The plate 16 is provided with an opening conforming with the grouping of the burner tubes and the outer tubes are partly surrounded by serrations 23 of the plate 16 in such a manner that air coming from below, between the baffle posts 8, is di- 110 rected to flow completely and equally around said outer tubes as well as around all of the other tubes.

Gas flowing through supply pipe 13 is controlled by an ordinary gas cock 24, but it 110 will be understood any other suitable gas controlling means may be employed. In ac-

cordance with the present invention an equal and uniform supply of air is distributed to each flame jet in sufficient amount to insure complete combustion of the gas irrespective 5 of whether or not the gas has received a pre-mixture of air before coming to the point of ignition. By the present means all the air necessary for super-combustion is supplied to the flames even when burning gas which 10 has not received a pre-mixture of air, and thus the Bunsen principle need not necessarily be employed. Secondly, by means of the present improved means for the distribution of air to the flames, the advantage obtained 15 with the Bunsen burner is enhanced, therefore, the same may be used advantageously in conjunction with the improvements herein described if desired.

It should be noted that the air supply 20 to the flame jets is indirect, the purpose of the outer posts being to prevent any atmospheric air from flowing directly against any of the outer burner tubes or flame jets of the group. All the air which is supplied 25 to the flames is caused to flow first into the passages between the posts and the burner tubes, from which passages the air distributes itself equally and uniformly to all sides of all the flame jets and by means 30 of said posts the air inflow is decreased in volume and increased in velocity, thus equal distribution even to the innermost flame jets of the group is accomplished, consequently these posts insure an equal distribution 35 of air to all the flame jets of the group.

The burner tubes are spaced at substantially equal distances apart to form a group 40 preferably hexagonal in shape and to provide an equal air space around each flame jet for the purpose, firstly, to insure an equal distribution of air to each flame jet, and secondly, to prevent the products of combustion from returning and suffocating 45 the flames.

The group of burner tubes is surrounded as previously stated by the baffle posts which 50 are preferably spaced around the burner tubes to define the air passages, and these posts preferably increase in thickness from their tops downwardly to form spaces between one post and another of greater area at the top than at the bottom, the upper or greater area carrying the air required to 55 be distributed to supply the outer or greater area of the space occupied by the outer burner tubes and the lower or lesser area carrying the air required to be distributed to supply the inner or lesser area of the 60 space occupied by the inner burner tubes.

The flanged plate 16 carried by the baffle posts serves to position the burner when used in connection with an oven or inclosed heating chamber and directs the air laterally inward between the posts and the

burner tubes, and its inner edge is spaced at a proper distance from the outer burner tubes to provide the correct air space around the flame jets thereof.

I desire it to be understood that the 70 burner is used for the purpose of heating pots and pans. The upper portion or covering member 3 may be dispensed with, in which case the complete burner will consist of the body portion 1 and the lower 75 portion or gas distributor 2.

If desired the covering member 3 may be removed and a grid of the usual form substituted to support pots and pans.

It is obvious that modifications may be 80 made in the construction as described hereinbefore without departing from the spirit of the invention defined in the appended claims, for example, the grouping or arrangement of the burner units may be in 85 some form other than hexagonal in shape.

Furthermore, it will be understood, that the various parts thereof may be cast integral with each other if desired without lessening the efficiency of the burner. 90

Having described my invention, what I claim as new and desire to secure by Letters Patent, is:—

1. In a burner of the class described; a plurality of burner units; a flanged member 95 around said burner units; a plurality of baffle units surrounding said burner units and supporting said flanged member; and all of said units being equally spaced so as to define a plurality of air passages 100 from different angles between all of said units under said flanged member.

2. In a burner of the class described; a plurality of burner units; a plurality of baffle units surrounding said burner units; 105 all of said units being equally spaced apart so as to define a plurality of air passages from different angles between all of said units; and a flanged member supported on said baffle units whereby supply of air 110 for combustion is confined to such supply obtained through said air passages.

3. In a burner of the class described; a flanged member; a plurality of burner units under said flanged member; a plurality of baffle units surrounding said burner units and supporting said flanged member; all of said units being equally spaced apart so as to define a plurality of air passages from different angles between 115 all of said units, and said units diminishing in diameter from the base toward the top so as to correspondingly increase the area of said air passages toward the tops of said units.

4. In a burner of the class described; a flanged member; a plurality of burner units under said flanged member; a plurality of baffle units surrounding said burner units and supporting said flanged member; 130

all of said units being equally spaced apart so as to define a plurality of air passages from different angles between all of said units, and said units diminishing in diameter from the base toward the top so as to correspondingly increase the area of said air passages toward the tops of said units.

5. In a gas burner; a plurality of burner tubes; a plurality of posts surrounding said burner tubes, said burner tubes and said posts being spaced apart at substantially equal distances from each other to form a group hexagonal in shape.

6. In a gas burner; a plurality of burner tubes; a plurality of posts surrounding said burner tubes, said burner tubes and said posts being spaced apart at substantially equal distances from each other to form a group hexagonal in shape and to form air passages between said burner tubes and posts.

7. A gas burner having multiple burner units grouped together to form multiple air passages between said burner units; a series 25 of baffle units surrounding said burner units and initially defining said air passages; and a flanged plate or member supported upon said baffles and restricting admission of air supply for the burner units to that obtained 30 through said air passages.

8. A gas burner having multiple burner units grouped together to form multiple air passages between said burner units; a series of baffle units surrounding said burner 35 units and initially defining said air passages; a flanged plate or member supported upon said baffles and restricting admission of air supply for the burner units to that obtained 40 through said air passages; and a vertical flange or guard carried by said plate or member defining a space or combustion chamber for said burner units.

9. A burner of the class described composed of separable sections, one section constituting a body having multiple burner units and multiple baffle units surrounding 45 said burner units, said baffle units in conjunction with said burner units defining air passages between all the units, and another 50 section constituting a covering member supported upon said baffle units and forming a combustion space for said burner units and directing all the air for combustion admitted

to said burner units to pass through said air passages.

10. A burner of the class described composed of separable sections, one section constituting a body having multiple burner units and multiple baffle units surrounding said burner units, said baffle units in conjunction with said burner units defining air passages between all the units, and another section constituting a covering member located above and forming a combustion space for said burner units and directing all the 65 air for combustion admitted to said burner units to pass through said air passages, and a third section consisting of a lower member providing a gas distributing chamber communicating with said burner units. 70

11. A gas burner comprising a plurality of burner tubes spaced apart at substantially equal distances one from another; and a plurality of air baffle posts surrounding said burner tubes and spaced at similar distances 75 from said burner tubes and from each other.

12. In a gas burner; a plurality of burner tubes; and a plurality of posts surrounding said burner tubes, being spaced apart at substantially equal distances from each other 80 to form air passages of substantially equal area between said posts and burner tubes.

13. In a gas burner; a plurality of burner tubes spaced apart at substantially equal distances from each other and a plurality of 85 posts surrounding said burner tubes and spaced apart at substantially equal distances from said burner tubes and from each other.

14. A gas burner of the class described composed of a plurality of separable sections, one section constituting a body member and having a plurality of burner units and air supply governing baffles with defined air passages therebetween, another section constituting a covering member for said 95 units and baffles and having flanges around and adjacent to said units for guarding the flames of said burner units and directing air for combustion to said air passages, and a third section providing a gas distributing 100 chamber communicating with said burner units.

In testimony whereof I have hereunto affixed my signature.

JOHN H. ACKROYD.
